Primary Examiner — John Windmuller(74) *Attorney, Agent, or Firm* — Kirk A. Buhler; Buhler & Associates(57) **CLAIM**

The ornamental design for a mot-spot antenna dish, as shown and described.

DESCRIPTION

FIG. 1 is a front perspective view of a mot-spot antenna dish showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in FIG. 3 depict environmental subject matter only and form no part of the claimed design.
